UNITED STATES PATENT OFFICE.

BOYD E. RAINY, OF ST. LOUIS, MISSOURI.

HOT-AIR FURNACE.

1,171,245.

Specification of Letters Patent.

Patented Feb. 8, 1916.

Application filed December 7, 1914. Serial No. 875,933.

To all whom it may concern:

Be it known that I, BOYD E. RAINY, a citizen of the United States, and residing at St. Louis, in the State of Missouri, have invented a certain new and useful Improvement in Hot-Air Furnaces, of which the following is a specification.

This invention relates to furnaces, and more particularly to furnaces having a double jacket and a single register.

One of the objects of this invention is to construct a double jacket furnace having improved means for supporting the casings in spaced relation with respect to the furnace body and the furnace front to form a rigid structure.

Another object is to construct a double jacket furnace having a single register and provided with improved connections between the casings and the front.

Further objects will appear from the detail description taken in connection with the accompanying drawings, in which:

Figure 1 is a front elevation of a furnace embodying this invention; Fig. 2 is a vertical section on the line 2—2, Fig. 1; Fig. 3 is a detail perspective of the lower part of the furnace, the front and part of the furnace body being removed and the outer casing being cut away; Fig. 4 is an enlarged section on the line 4—4, Fig. 1; Fig. 5 is an enlarged detail section on the line 5—5, Fig. 1; and, Fig. 6 is an enlarged detail section of Fig. 2.

Referring to the accompanying drawings, the furnace body consists of an ash pit 10, a fire pot 11, and a radiator 12 discharging into a smoke-pipe 13. The ash pit 10 is provided with a forwardly projecting ash pit passage 14, the fire pot with a forwardly projecting fire door passage 15, and the radiator with a forwardly projecting clean-out passage 16. The furnace body sets on a base 17, provided with a ring 18 integral therewith, but spaced from the furnace body at the rear side of the furnace and connected thereto by radial arms 20, integral with the base and the ring. This ring is shouldered as shown at 19.

A front, preferably of cast iron, and which may be a single piece or composed of one or more sections 21 bolted together as shown at 22, sets on the base 18 of the furnace body and is bolted to the passages 14, 15 and 16 thereon. This front is preferably of the "dished" type to shorten the

length of the passages 14, 15 and 16, and is provided with forwardly projecting side flanges 23 and a forwardly projecting top flange 24. The flanges 23 and 24 are turned laterally and upwardly, as shown at 25 and 26 respectively. The front is provided with fire and ash pit doors 27 and 28, and with a removable door or plate 29 for the clean-out passage 16. In order to locate and retain the front in position on the base 18, the base is provided with lugs 30 engaging the front, and the flanges with lugs 31 engaging the base, the lugs cooperating with one another and with the shoulder 19.

A continuous ring 32, preferably of T-section, is supported at its front portion on the upper flange 24, and may be bolted to the edge 26 of the flange. The outer casing 33 may be a single piece, or it may consist of a pair of sections secured, at their ends, to the edges 25 of the side flanges 23 by bolts 34, or otherwise. When the casing is made up of sections, the latter are joined in the usual way by a strip 35 of T-section; this strip is, however, only a joining member and is not, therefore, directly attached to the front but only extends to the edges 25 of the flanges so as to abut thereagainst, in order not to break the continuity between the casing sections and the flange. The bolt 34, between the sections 33, preferably passes through a plate or washer 36 to draw the casing up tight. The outside casing, whether single or in sections, rests, at its bottom, on the continuous base ring 18, and engages, at its upper end, the continuous top ring 32. This casing may be secured to the top ring by bolts, although this will be ordinarily not necessary.

The inside casing 37 has its ends bent outwardly, as shown at 38, and laterally, as shown at 39, to form flanges adapted to engage the outturned edges 25 of the front, and these flanges are clamped between the outside casing and the front, as shown in Figs. 4 and 5. These flanges 39 need not be perforated, since they are clamped by the bolts 34 and the outside casing 33 in the corners formed between the body and the edge of the front flanges. The bottom of the inside casing is about on a level with the ash pit, and this bottom is stiffened by the usual T-shaped strip 40, which is attached to the casing by bolts in the usual manner. This strip 40 is not attached to the front, but terminates at the turned out

ends 38 of the inner casing. This permits an easy application of the strip after the inside casing is in place. The casing is supported by a series of shouldered braces 5 or legs 41 attached to the strengthening strip by bolts 42 and having forked ends 43 embracing the arms on the base. A continuous ring 44 of T-section rests on and caps the inside casing, and may be attached thereto by a few bolts. A casing 58 is hung from the ring 44 in spaced relation to the inside casing to provide an inside air space.

Continuous inner and outer casing sections 45 and 46 rest on and are supported by the rings 44 and 32. These casing sections may be bolted to the rings, or simply rest thereon.

Spaced frusto-conical inner and outer casing connections 47 and 48 respectively, 20 are provided with straight cylindrical necks 49 and 50 respectively, engaging flanges 51 and 52 respectively, of a single register 60 set into the floor 61, as shown in Fig. 2. These connecting sections are preferably 25 secured together by braces 53, so as to form a unitary structure. The lower ends of these connections are provided with flanges 54 and 55, formed to provide shoulders 56 and 57 respectively, so as to telescope with 30 and rest on the inner and outer casing sections 35 and 46 respectively. In this type of furnace only a single register is used, and this register comprises a central section 58* and an outside annular section 59, separated by the flange 51.

A water pan 62 is attached to the casing 33 and projects into the air space, the open projecting part 63 being located below the inside casing, as shown in Fig. 1. The pan 40 is provided with a removable cover 64. The outside casing has, on its opposite side, the usual opening closed by a slide 65.

The general operation of this furnace is well known. The cold air enters the annular section 59 and travels downwardly within the outer jacket and upwardly within the inner jacket, and issues into the room through the central section 58*. By constructing both connections 47 and 48 of 45 conical form, there will be no interference with the air currents, whether descending or ascending. The continuous ring 32 and 44 result in a braced construction, and also one which admits of the furnace being readily assembled. By constructing the outside casing of a single piece of metal, or of sections connected by a joint which terminates at the front, the joint between this front can be made tight. It will thus be seen 50 that the outside casing is supported by continuous rings, both at the top and bottom; while the inside casing is capped by a con-

tinuous ring at the top and is supported on the furnace body at the bottom. The inside casing is so formed that it can be readily assembled and, when assembled, will be held by its turned edges 38 and the flanges 39 thereon in fixed definite relation with respect to the outer casing. The outside casing, as well as the inside casings 37 and 58, are, therefore, wholly supported by the edges 25 of the front. This permits either a dished or an undished front to be used. The location of the water pan below the bottom of the inside casing causes the descending currents to impact upon the water, and thus uniformly moisten the air before it is heated. The slide 65 can be opened to regulate the air currents.

It is obvious that various changes may be 80 made in details of construction without departing from the spirit of this invention, and it is, therefore, to be understood that this invention is not to be limited to the specific construction shown and described.

Having thus described the invention, what is claimed is:

1. In a double jacket furnace, a furnace body, a front wall secured thereto and having forwardly projecting side flanges provided at their outer edges with laterally projecting portions, inner and outer casings forming with said furnace body inner and outer jackets communicating at their base, the edges of said inner casing having outwardly turned flanges to engage said outer casing at a point within the angle formed by said side flanges and their laterally projecting portions, means securing the edges of both of said casings at their point of engagement to the laterally projecting portions of said side flanges, and a register connected with said casings and having inner and outer sections communicating respectively with said jackets.

2. In a double jacket furnace, a furnace body, a front wall secured thereto, inner and outer casings arranged in spaced relation and forming with said furnace body inner and outer jackets communicating at their base, a ring on said inner casing, a casing spaced from said inner casing and suspended from said ring and forming an insulating space between said inner and outer jackets, and a register connected with said casings and having inner and outer sections communicating respectively with said jackets.

In testimony whereof I affix my signature in the presence of these two witnesses.

BOYD E. RAINES.
